United States Patent Office

Des. 226,444
Patented Mar. 6, 1973

226,444

TROLLEY JACK

Bertram Donald Granger, Wollaton, Nottingham, England, assignor to Newman Granger Industries Limited

Filed Sept. 29, 1971, Ser. No. 184,977

Term of patent 3½ years

Int. Cl. D15—99; D12—05
U.S. Cl. D41—1 D

FIG. 1.

FIG. 2.

FIG.3.

FIG.4.

FIG.5.

FIG. 1 is a perspective view from above showing the trolley jack in a semi-elevated position;

FIG. 2 is a perspective view from beneath and from the opposite side to FIG. 1 showing the jack in a semi-elevated position;

FIG. 3 is a side view of the trolley jack;

FIG. 4 is a view from overhead in plan of the trolley jack;

FIG. 5 is a view from one end of a trolley jack.

I claim:

The ornamental design for a trolley jack, as shown.
